FABRIC TAKE-OFF DEVICE FOR FULL-FASHIONED KNITTING MACHINES AND METHOD OF OPERATING SAME

Herbert Erich Haehnel, West Reading, Pa., assignor to Textile Machine Works, Wyomissing, Pa., a corporation of Pennsylvania

Application April 26, 1947, Serial No. 744,244

18 Claims. (Cl. 66—96)

1

The present invention relating to full-fashioned knitting machines, more particularly concerns new and improved apparatus forming a part of the welt-turning and draw-off mechanisms of such machines and a novel method of operating the same.

It has been found, in the present types of welt turning mechanisms, that the use of two fabric tensioning or draw-off devices promotes simplicity in design and operation of said welt turning mechanism. These devices comprise ordinarily an auxiliary draw-off means for applying tension to the welt bars during knitting of the welt, and another, the so-called main draw-off means, used to tension the welt wires during certain phases in knitting of the welt and for tensioning the fabric after the turning of the welt. However, in employing two different draw-off means in the formation of the welt, difficulties in operation have been encountered, particularly immediately following the closing of the welt where both draw-off means apply an excessive amount of tension to the fabric.

Heretofore, immediately after the welt has been turned and before yarn has been laid for a new course, it has been necessary to stop the machine in order to prevent the further application to the fabric of the tension up to then supplied by the auxiliary draw-off shaft, and in order to release the tension of the auxiliary draw-off means from the welt bars, the auxiliary draw-off shaft was manually turned in a direction reverse to the draw-off movement of said shaft and latched in said position before again starting the machine. In releasing the tension of the auxiliary draw-off means some of the draw-off straps were disconnected from the welt bars but others remained in engagement with their respective welt bars and had to be manually released before disengaging the welt bars from the fabric. After all the straps were released from the welt bars and the machine again started, the auxiliary draw-off shaft was manually rotated to position the straps for the start of the next set of stockings. The welt bars were then disengaged from the fabric and placed in position to start the next welt and the draw-off straps were attached thereto.

It is accordingly an object of the present invention to provide a novel means for and method of hooking up and turning welts which will reduce certain of the manual operations and thereby increase the output and improve the quality of the fabric produced by a full-fashioned knitting machine.

2

A further object of the invention is to provide means in an automatic welt-turning mechanism for full-fashioned knitting machines which will automatically make certain, when required, the release of the hooks and tension draw-off devices from the welt bars.

Another object of the invention is to provide a means adapted to release the auxiliary tension of a full-fashioned knitting machine and to hold said tension mechanism inactive as long as desired.

Still another object of the invention is to provide a novel hook for engaging a welt bar of a full-fashioned knitting machine and which is so constructed as to insure its quick and sure self disengagement from the welt bar after the draw-off tension on the strap for the welt bar has been released and upon continued knitting and drawing off of fabric.

Still another object of the invention is to provide a full-fashioned knitting machine with a novel power operated means for releasably latching an auxiliary draw-off shaft.

With these and other objects in view, which will become apparent from the following detailed description of the illustrated embodiment of the invention shown and described in the accompanying drawings, the invention resides in the novel elements, features of construction and arrangement of parts in cooperative relationship and the improved method of operating the same, as hereinafter more particularly pointed out in the claims.

In the drawings:

Fig. 1 is an end elevation of a full-fashioned knitting machine within the invention having both auxiliary and main draw-off means, parts being shown both in section and dot and dash outline, and other parts being omitted for purposes of illustration;

Fig. 2 is a fragmentary front elevation, broken in several places, of certain parts shown in Fig. 1;

Fig. 3 is a detailed view taken substantially along the line 3—3 of Fig. 2;

Fig. 4 is a detailed view taken substantially along the line 4—4 of Fig. 2;

Fig. 5 is a detailed view taken substantially on the line 5—5 of Fig. 2 looking in the direction of the arrows;

Fig. 6 is a detailed view, partly diagrammatic in character, of certain of the parts shown in Fig. 1, but with the parts in the position immediately following the turning of the welt;

Fig. 7 is a detailed view similar to Fig. 4 but

with the parts in the position corresponding to the position of the parts shown in Fig. 6;

Fig. 8 is a view similar to Fig. 6 but with the parts in different relative positions;

Fig. 9 is a view similar to Fig. 7 but with the parts in positions corresponding to those of the parts in Fig. 8;

Fig. 10 is a detailed view, partially in section, of the hook member connecting the draw-off strap and welt bar as shown in Fig. 8 but enlarged relative thereto;

Fig. 11 is a view similar to Figs. 6 and 8 but with certain of the parts in different positions relative thereto;

Fig. 12 is a view similar to Figs. 7 and 9 but with the parts in a position corresponding to the position of the parts in Fig. 11;

Fig. 13 is a view similar to Figs. 6, 8 and 11 with certain of the parts in different positions relative thereto;

Fig. 14 is a view similar to Figs. 7, 9 and 12 but with the parts in a position corresponding to the position of the parts in Fig. 13; and

Figs. 15 and 16 are fragmentary detailed views showing the hook for one of the welt bars in successive positions assumed by it prior to the point in the cycle shown in Fig. 11.

In the drawings and description, only the means and method necessary to a complete understanding of the invention have been specifically set forth; further information as to the construction and operation of other related, usual and well known knitting machine elements, mechanisms, etc., may be found in one or more of the following publications:

1. Pamphlet entitled—Full-Fashioned Knitting Machines—published and copyrighted by the Textile Machine Works, Reading, Pennsylvania, in 1920.

2. Three catalogs entitled—The “Reading” Full-Fashioned Knitting Machine Parts Catalog—published and copyrighted by the Textile Machine Works, in 1929, 1935 and 1940, respectively.

3. Booklet entitled—The “Reading” High-Production Full-Fashioned Knitting Machine—which forms a supplement to the above noted 1940 Parts Catalog of the Textile Machine Works, a publication of the Textile Machine Works, copyrighted in 1940.

4. Pamphlet entitled—Knitting Machine Lectures—published by the Wyomissing Polytechnic Institute, Wyomissing, Pennsylvania, in 1935.

In the embodiment of the invention herein shown and described, there is combined with certain well known parts of a full-fashioned knitting machine, improved fabric tensioning and draw-off mechanism comprising a latch or like means adapted to hold an auxiliary draw-off shaft so that its strap becomes loose enough for its hook to disengage itself from its welt bar soon after said latch means has been put into action to hold the shaft against turning. Said latch means preferably automatically operates to engage the auxiliary draw-off shaft periodically and at a certain angular position thereof. The draw-off mechanism, of which said auxiliary shaft and strap forms a part, may be of a generally known form having a weight connected by a cable to a sheave or pulley for applying a torque to the auxiliary draw-off shaft in the direction to draw off fabric as knitted, there being as shown, however, no stop for the weight so that the cable is always under tension.

Also, the present illustrated knitting machine

includes a power operated welt turner and a main draw-off means having straps to be attached to a welt wire or welt wires and preferably of the type having both a weighted cable and cam energized springs (not shown) for applying a torque to the main draw-off shaft in the draw-off direction, said auxiliary draw-off means acting only until the welt has been partially formed and the main draw-off means then taking over the draw-off function by acting on welt wires in folds of the welts. Said latch means for the auxiliary draw-off shaft acts for a time to substantially prevent any tension in the straps between the welt bars and the auxiliary draw-off shaft by holding the auxiliary shaft stationary in the position which it reached when turned in the non-draw-off direction. The main draw-off means, however, acts while fabric is knitted after the welts have been turned and the welt bars ride along on, or are drawn along by, the fabric so that the auxiliary draw-off straps sag down against the fabric and the combined effect of the characteristics and motions of the parts causes all the hooks on the welt-bar straps to disengage themselves from the welt bars. The auxiliary shaft is then released and returned to position for the start of the next welt and latched in such position. The welt hooks may then be disengaged and the welt bars placed in position for the start of the next welt and the auxiliary draw-off straps again engaged to the welt bars, the straps applying only a slight tension on the welt bar as determined by the auxiliary shaft.

The auxiliary draw-off shaft may be manually turned in the non-draw-off direction when desired but it has been found advantageous to turn it in the reverse or non-draw-off direction automatically by cam action as well as to latch the shaft automatically, while further advantageous features of the auxiliary draw-off means are disclosed herein as regards the form of hook used between the welt bars and their straps.

Referring to Fig. 1 of the drawings, there is shown therein a portion of a multi-section full-fashioned knitting machine of the “Reading” type comprising a frame-work including transverse frames 21, front beam 22, back beam 23, center-bed 24 and front bed or table 25, a main camshaft 26, and a plurality of knitting sections, parts of three of which are shown in Fig. 2 in position to form a single section 30. Each knitting section 30 comprises knitting means including a row of knitting needles 31, shown as of the spring beard type, a sinker-head 32 having sinkers 33 and dividers 34 therein for cooperating with the needles 31 in forming loops of yarn to be knitted. Two draw-off means, 35 and 36, are provided, as shown in Figs. 6, 8, 11 and 13. Draw-off 35 is an auxiliary mechanism and has a draw-off shaft 37 with reels such as 38 thereon, one reel for each knitting section. Each reel 38 has a draw-off strap 39 shown as having one end connected to the reel, the other end of said strap having a hook 40 whereby the strap 39 may be connected to a welt bar 41 to exert a draw-off tension on a piece of fabric. To this end, welt bar 41 is provided with a loop member 42 fixed to one side or edge thereof with which hook 40 is adapted to be engaged, as shown in Figs. 6, 8 and 10. The opposite side or edge of bar 41 has a set of welt hooks 43 fixed thereto projecting toward the needle row 31 and engaged with the loops of the first course of a fabric in well known manner to draw-off the fabric as it is knitted.

The auxiliary draw-off means, including hook

40, is shown, and will be further described, in connection with a particular hook-up and welt turning means which is not per se a part of the present invention.

The hook 40 is so constructed that it will be reliably disengaged from the loop 42 as herein-after set forth. For this purpose, the hook has its free end rounded as shown and its inner or engaging surface has a material straight length 47 inclined upward when the hook is in a position to engage the loop member 42 on the welt bar 41. As shown in Fig. 2, auxiliary draw-off shaft 37 is provided with pulley 44 of the sheave type to which is connected one end of a cable 45, the other end of which is fixed to a weight 46, as diagrammatically shown in Figs. 6, 8, 11 and 13, to exert a torque on shaft 37 in the draw-off direction. The auxiliary draw-off means begins to act immediately upon the engagement of welt hooks 43 with loops of the first course of the welt. In the arrangement shown, each welt bar 41 is adapted to slide on rails 50 on the front bed 25, as shown in Figs. 1 and 2. The bar 41 is moved from a rest position shown in Fig. 13 to a hook-up position and a welt closing position, shown in Fig. 1. In the rest position shown in Fig. 13, the welt bar 41 is held against pins 51 carried in links 52 and forming parts of a pusher means used in moving the welt bar towards the needles. The pins 51 are adapted also to position the welt bar lengthwise of the needles 31 so as to align the welt hooks 43 with the spaces between the needles. As shown, the other ends of links 52 are pivotally connected to levers 53 fixed in turn to a shaft 54.

For moving the pins 51 and bar 41 toward the needle row for hooking up, shaft 54 is provided with a gear not shown but having teeth adapted to mesh with those of a rack member 55 so that the position of the member 55 controls the angular position of shaft 54 and the position of pins 51 and determines the movement of the welt bar 41 toward the needle row. The rack member 55 is guided and supported in a housing 56 shown as carried on needle presser shaft 57 and fixed to the front bed 25 of the machine. The housing is further supported by a rod 58 connected to front beam 22. The lower end of rack 55 is pivotally connected to a link 60 which is pivotally connected in turn to one end of a lever 61, the rear end of which is pivoted to a bracket 59 fixed to the back beam 23 of the machine. The other end of lever 61 carries a roller-type cam follower 62. Lever 61 is urged toward the cam shaft 26 by a tension spring 63 so that follower 62 follows, when in proper position, the contour of any one of a group of three cams of which two, 64 and 65, are shown and with which it is adapted to cooperate to raise the rack 55 and thereby move the pins 51 and bar 41 from their rest positions toward the needle row. When the rack 55 and associated parts are in the rest position, the lever 61 is in its lowest position in which a bolt 68 fixed in lever 61 rests against the upper face of an arm 69 of the bracket 59. A means is provided for controlling the shifting of the roller 62 from an inactive position at one side of said group of cams into the plane of whichever cam of the group it is desired should actuate the rack 55 and pins 51. Said means is shown as including a rod 70 the lower end of which is pivotally connected to a lever 71 adapted to be controlled by the usual pattern chain mechanism (not shown) to shift roller 62 as desired. The mechanism for operating the welt

bar and the control means therefore is more fully shown and described in Bitzer Patent No. 2,413,601, December 31, 1946.

Assuming follower 62 has been shifted at the proper point in the revolution of shaft 26 to cooperate with the cam 64, rack 55 is lifted to turn levers 53 in the counter-clockwise direction as viewed in Fig. 1 to push pins 51 and welt bar 41 toward the needle row so that the welt hooks extend between the needles. The loops of a first course having been formed by the action of sinkers 33 and dividers 34 in pressing yarn between the stems of the needles, the needles are then brought down so that the loops catch under the beards of the needles and the loops are drawn down off the nibs of the sinkers onto the hooks 43.

The first course of loops of a welt having been engaged by hooks 43, rack 55 is lowered by cam 64 until pins 51 are in the stop or rest position shown in Fig. 6, the lever 61 then being supported on arm 69. The bar 41 is, however, held at this time near the needle row by the engagement of hooks 43 with the fabric loops and, as knitting progresses, the welt fabric is drawn off by tension supplied to the welt bar through auxiliary draw-off shaft 37, reel 38, strap 39 and hook 40. After a certain amount of welt fabric has been knitted, the main draw-off means 36 goes into action to draw off the fabric. For this purpose, means 36 includes a draw-off shaft 72, a reel for each section such as 73 fixed on shaft 72 which is turned at the desired time contrary to the draw-off direction to unwind straps 74 connected to reel 73, thereby running hooks 75 on straps 74, or permitting them to be drawn, toward the needle row and latched in a position (by means not shown) for engagement of the hooks 75 with a welt wire 76, in well known manner. The shaft 72 is rotated in the draw-off direction by a weight (not shown) attached by means of a rope or cable 77 to a pulley 79 secured to the shaft 72, or by an automatic spring tensioning device shown in the hereinbefore referred to 1940 Parts Catalog and both shown and described in the patent to Bitzer, No. 2,295,512, September 8, 1942. The welt wire 76 is then placed by an operative on top of the welt fabric and into a groove 67 in each of the rails 50, in the desired position to be engaged by the hooks 75 on draw-off straps 74.

In this position, the welt hooks 43 being above the level of groove 67 the tension of the fabric holds the welt wire against the upper horizontal edge of the groove.

To facilitate insertion of the welt wires 76 into the grooves 67 for subsequent engagement by the hooks 75, rails 50 are provided with downwardly inclined slots 109 along their inner faces the edges of one of which appear in Figs. 11 and 13. Each slot 109 has a slider or plunger 110 therein which, as clearly shown in Fig. 13, is provided with a groove 111. Each plunger 110 is yieldably biased by a spring 112, shown in Figs. 1 and 6, to the position shown in Fig. 13 in which the groove 111 is in alignment with the groove 67 in the rail 50. By pressing welt wires 76 down on the upper ends of plungers 110, the plungers are readily forced down until their upper ends are level with the bottoms of grooves 67 so that the ends of the welt wires pass into the grooves. Thereupon, the plungers move back automatically to the position shown in Figs. 6, 8, 11 and 13 leaving the welt wires 76 in position to be engaged by hooks 75 as soon as the hooks are free to yield to the draw-off tension of the means

36 and to draw the fabric forward as indicated in said figures and as hereinafter set forth.

After a certain further amount of welt fabric has been knitted, the pattern means moves cam follower 62 into the plane of cam 65 to move the pins 51 to engage the welt bar 41 and to move it to a position intermediate the rest position of the pins and the needle row. Means are provided, including a lever 78 pivoted on lever 61 and cooperating with the arm 69, to hold the welt bar 41 in said intermediate position until another operation of the pins 51, said means being well known and not further described herein. As shaft 54 and levers 53 are moved by cam 65, the hooks 75 and straps 74 are released from the latching means whereby the hooks 75 are drawn into engagement with the welt wire 76 to apply a draw-off tension thereto. As the grooves 67 in the rails 50 are on a level below that of the welt hooks 43, the application of draw-off tension to the welt wire produces a fold in the welt fabric and pulls the loops on the hooks 43 toward the welt bar 41, and against pusher elements 80 on the shanks of hooks 43 to position the loops for restoration to the needles when desired. Cam 65 having passed from beneath follower 62 but leaving the lever 61, rack 55, pins 51 and welt bar 41 held by lever 78 and arm 69 in its intermediate position knitting is continued until enough fabric has been formed to complete the welt. Thereupon the third cam (not shown) in the group containing cams 64 and 65, is thrown into action by the pattern means and lever 71. Said third cam is of the same height as cam 64 and therefore moves pins 51 from their intermediate position to the same point as the pins were moved by cam 64 thereby moving the welt bar 41 toward the needle row until the hooks 43 project between the needles as at the time of hooking up.

With the welt hooks 43 in position to return the loops held thereon to the needles as the needles rise in the revolution during which said third cam operates, they pass through the sinker loops held against pusher elements 80 on hooks 43, thereby closing the welt. The position of the parts at this time is not shown but after the needles have passed through the loops of the first course, the pusher pins 51 are withdrawn to their rest position whereby if no action were taken to prevent it, the full tension of the shaft 37 would be exerted on welt bar 41 through strap 39 and hook 40 while main draw-off means 35 exerts its full tension on the fabric through straps 74, hooks 75 and welt wire 76, as shown in Fig. 6.

In order that knitting can be continued without interruption but without the combined tensioning effect of draw-off means 35 and 36 on the fabric, means are provided to turn auxiliary draw-off shaft 37 in the non-draw-off or reverse direction to substantially release the tension of the auxiliary means 35 immediately after the welt loops held on the welt hooks 43 are returned to the needles. For the purpose of releasing the tension on the fabric, a disk 83 (shown in Figs. 2 and 4) having a notch 84 therein is fixed on shaft 37 and a lever 85, Figs. 2, 4 and 5, is pivotally mounted at one end on shaft 37 and has a pawl or dog 86 pivoted to its other end by a pin 87. A spring 88, Figs. 2 and 5, urges dog 86 toward a position in which it engages notch 84 but normally the dog is held out of engagement with the notch as otherwise rotation of shaft 37 in the draw-off or clockwise direction, as viewed in Fig. 4, would be prevented. For retaining dog 86 normally free of

notch 84 as shown in Figs. 4 and 7, the dog is provided with an off-set lug 89 adapted to engage a fixed pin 90 when the dog 86 is in its lowest or inactive position, as shown in Fig. 4. For moving dog 86 to turn disk 83 and shaft 37, the upper end of a link 91 is pivoted to pin 87 from which point said link extends downwardly to a pivoted connection with the front end of a lever 92 pivoted to one of the frames 21 as shown at 93 in Fig. 1. Lever 92 has an arm 94 extending upwardly therefrom and having a stop bolt 95 fixed in an offset at the upper end of arm 94. When dog 86 and lever 92 are at their lowest levels and bolt 95 contacts a portion of one of the frames 21, as shown in Figs. 1 and 2, a spring 82 holds link 91 so that dog 86 presses on pin 90 and the dog is held in its inactive position with relation to disk 83. Lever 92 also is provided with a further arm 96 extending downwardly therefrom and having pivoted thereto at its lower end a roller type cam follower 97, for cooperation with a cam 81 but normally positioned out of the plane of said cam. Follower 97 is shiftable to the right, as viewed in Fig. 2, along its pivot 98 parallel to the main camshaft 26 into active position or into the plane of cam 81 by a member 99 shown as fixed to a horizontal rod 100 controlled from the pattern mechanism of the machine (not shown). Shifting of the follower 97 into active position compresses a spring 107 between the follower and the arm 96, the spring acting to shift the follower to inactive position or out of the plane of the cam 81 when the member 99 is permitted to return to its position of Fig. 2 by the aforementioned pattern mechanism. As soon as the welt has been closed as shown in Fig. 6, cam 81 swings lever 92 upwardly to lift link 91 and dog 86 whereby the dog engages in notch 84 and the further movement of lever 92 in response to the rotation of cam 81 throws dog 86 and shaft 37 in the non-draw-off direction and into the position shown in Figs. 8 and 9 and in which the tension in strap 39 is almost entirely relaxed. A latch 102 pivoted on a bolt 101 carried on the frame near the end of the machine at which sheave 44 is located is biased by a spring 105 (Fig. 3) to press against a disk 104 fixed to shaft 37 as shown in Fig. 8. Also, said disk has a notch 103 shown in Fig. 6 and so placed that, in the positions of the parts shown in Figs. 8 and 9, latch 102 presses into said notch and, as the dog 86 and link 91 are returned to inactive position, Fig. 12, the latch 102 remains in engagement with an edge 108 of notch 103 thereby holding shaft 37 in the position shown in Figs. 8 and 9 until it is desired to throw the latch out of engaging position. At the time latch 102 engages edge 108 of notch 103, the tension exerted on strap 39 by springs 106 with which such straps are ordinarily provided is also substantially relaxed thereby forming a loop in the strap as shown in Figs. 8 and 11 between the points of the strap connected to ends of the springs 106 but there is still sufficient tension remaining in springs 106 in the position shown in Fig. 8 to hold the strap slightly tensioned. Knitting then continues, the main draw-off means 36 acting on the fabric while the tension in strap 39 is so slight as to be negligible so far as the fabric is concerned. As additional courses are knitted and with the welt hooks 43 remaining in the fabric, the slight tension in the strap 39 is sufficient to carry the welt bar 41 along with

the fabric away from the needles and toward shaft 37. As knitting continues the strap 39 is gradually slackened so that it bows downward and hook 40 edges rearward with relation to loop 42 of welt bar 41 from the position shown in Fig. 8 to that shown in Fig. 15. Due to the vibratory action in the fabric caused by the usual needle movements toward and away from the presser of the machine the hook 40 shakes itself out of the loop member 42 and drops onto the fabric as shown in Figs. 11 and 16. In the arrangement shown, the disengaging action of each hook 40 is reliable so that all such hooks in a multi-section machine become disengaged at about the same time. The latch 102 may then be released from the notch 103 and shaft 37 and pulley 44 allowed to turn to run the weight 46 to its lowest or rest position as shown in Fig. 13 in which the torque on shaft 37 again is held by latch 102. At this time, the notch 84 in disk 83 has turned to the position shown in Fig. 14. Now, the hooks 43 of each bar 41 may be disconnected from the fabric and the bar placed in rest position against pins 51 and the hook 40 of each strap 39 reconnected to the bar 41, as shown in Fig. 13, at any convenient time. The parts are so arranged and proportioned that when welt bar 41 stands in rest position and the hook 40 is attached to it by engagement with loop member 42 as in Fig. 13, there is sufficient tension in springs 106 to hold the short free length of strap 39 taut to hold hook 40 securely in place.

Further, the parts are so proportioned and their operations so timed that the latch 102, although always urged against its cooperating disk 104 by its spring 105, does not interfere with the movements of shaft 37 in hooking up, drawing off the welt and turning the welt because the disk 104 does not make a complete revolution as the welt bar 41 is moved from its rest position, Fig. 13, to its rearmost position shown in Fig. 1. Therefore, it will be seen that, except at the rest position at the extreme limit of movement of the shaft 37 in the draw-off direction, the notch 103 will not be engaged by latch 102 when shaft 37 turns in the usual draw-off and reverse movements but will be engaged by said latch member so as to be held against turning in the draw-off direction when given a further reverse movement by the dog 86.

The operation of an apparatus within the invention will be understood by those skilled in the art from the foregoing description. For purposes of convenience and to emphasize the essential steps of the novel method disclosed herein, the operation will be further described as follows:

Just before a set of welts is to be started on a machine of the type shown in the drawings, both the pusher pins 51 and the welt bar 41 will be in their rest positions shown in Fig. 13. For forming the first course in each knitting section, the yarn carriers (not shown) lay yarn on the nibs of the sinkers and dividers. The yarn is then sunk by the sinkers, divided by the dividers and the loops then engaged by the beards of the needles preparatory to drawing them down off the nibs of the sinkers and dividers onto the knock-over-bits. Prior to the point in the cycle at which the loops move down off said nibs, cam follower 62, which has been shifted by an impulse from the pattern means into the plane of cam 64, engages cam 64 so that the pins 51 are moved toward the needle row carrying with them the welt

bar 41 to a point at which the welt hooks 43 in the welt bars project between the needles and between the sinkers and dividers and the knock-over-bits. The forward movement of the pins 51 and bar 41 unwinds straps 39 and winds up cable 45 to lift weight 46. The needles then draw the loops of the first course down onto hooks 43 instead of onto the knockover-bits and the pins 51 are retracted to rest position leaving the loops engaged by the hooks 43 and tensioned by the weight 46 transmitted to the hooks by the straps 39. Preferably, alternate loops of the first course are then cast off before proceeding with the knitting of the welt.

After a portion of the welt has been knitted under the influence of draw-off means 35 of which weight 46 is a part, cam follower 62 is moved into the plane of cam 65 which is not as high as cam 64. Pins 51 are thereby moved to contact and move the bars 41 toward the needles to a position intermediate the needles and the rest position of the pins 51. The movement of the bars to said intermediate position is utilized to release the hooks 75 on the draw-off straps 74 of the main draw-off means 36 from positions near the needle rows to which they were previously moved and in which they had been latched. The welt bars 41 are latched in said intermediate position for completion of the welt while each pair of said hooks 75, as soon as released, are drawn forward into engagement with a welt wire 76 which had been placed on the fabric and held in the path of the hooks.

Welt wire 76 is guided in a horizontal path below the bar 41 so that it makes a fold in the fabric, the loops of the first course being drawn forward against elements 80 fixed on the shanks of the welt hooks 43. Both draw-off shafts are exerting tension on their straps at this time but, due to the fact that bar 41 is held by the pins 51, weight 46 has no effect on the fabric because the weight is attached directly to bar 41 which cannot then move, so that there is no undue tension on the loops.

After the desired length of welt fabric has been knitted, pins 51 are again moved toward the needle row to cause the hooks 43 to project between the needles as at the time of hooking up but, this time, for the purpose of closing or turning the welt. In closing the welt, the hooks 41 are held between the needles for a long enough period so that the needles come up through the loops of the first course. After the needles have reengaged the loops of the first course, the pusher pins 51 are withdrawn to their rest position leaving the bar 41 resting on the fabric with hooks 43 engaged in the loops. The combined tension of both draw-off means is, however, now acting on the loops, as shown in Fig. 6, and to avoid damage to the fabric the tension of weight 46 of the auxiliary draw-off means is now substantially taken off the loops before another course has been knitted. For this purpose, shaft 37 of the auxiliary draw-off means 35 is rotated in the reverse direction tending to unwind strap or straps 39 by engagement of the dog 86 in notch 84 in disk 83 as the dog is operated by the cam 81 through the lever 92 and link 91 from the position shown in Figs. 6 and 7 to that shown in Figs. 8 and 9. As the shaft 37 reaches the end of said reverse turn, it is releasably latched in position by the latch member 102 to hold the shaft at this point against the pull of the weight 46. As knitting continues after shaft 37 has been latched, bar 41 is carried along with the

fabric and as soon as sufficient fabric has been knitted after the welt has been closed to develop sufficient slack in the straps 39, the hook 40 on each strap 39 gradually relaxes its engagement with the loop 42 on bar 41 as shown in Fig. 15 until completely disengaged, as shown in Figs. 11 and 16 and as hereinbefore set forth. The straps 39 and hooks 40 having dropped to the position shown in Fig. 11, the welt hooks 43 of bar 41 may be disengaged from the fabric by the operatives when desired. Also, the shaft 37 may be unlatched and the shaft 37 allowed to rotate in the take-up direction to the position shown in Fig. 13 in which the weight 46 is again held by the latch 102, while bars 41 may be placed in starting position against the pusher pins 51 and the straps 39 again attached to the bars 41 preparatory to starting another welt, all as soon as desired after hooks 40 have disengaged themselves from the loops 42.

Of course, the improvements specifically shown and described by which the above results are obtained, can be changed and modified in various ways without departing from the invention herein disclosed and hereinafter claimed.

I claim:

1. In a full-fashioned knitting machine having a hooking up and welt-turning apparatus the combination of an auxiliary draw-off shaft having a strap provided with a hook, a welt bar having hooks engaging and applying tension to the loops of the first course during knitting of the welt, said bar engaged by the hook of said strap, a main draw-off shaft having straps connecting it to a welt wire in a fold of the fabric and applying tension to said wire while knitting fabric following the turning of the welt, and means reversing the movement of said auxiliary draw-off shaft after said main draw-off shaft has begun to act on the fabric and holding the auxiliary draw-off shaft to release the tension of the first strap for the auxiliary draw-off shaft to permit said hook of the first strap to disconnect itself from the bar.

2. In a full-fashioned knitting machine, the combination of an auxiliary fabric draw-off means including a welt bar, a draw-off strap, means for applying at times a draw-off tension to said strap, a hook on said strap for engaging the welt bar while the strap is under draw-off tension, means to release said tension for a desired time, and means for drawing off fabric during further knitting after the release of said tension and while the welt bar is being drawn along by the fabric, said hook being formed to disengage itself from the welt bar upon movement of the latter when the tension of its strap has been released.

3. The method of knitting a welt fabric on a full-fashioned knitting machine having a welt turning mechanism including a welt bar having hooks thereon for engaging the first course of a welt, an auxiliary draw-off shaft, a strap connected to said shaft and having connecting means connected to said welt bar during the knitting of the welt but formed to promote its automatic release from the bar upon release of tension thereon, and a main draw-off means for operation at least after formation of the welt, which comprises the steps of, releasing the tension of said strap while operating the machine to knit fabric and to draw the fabric off by said main draw-off means, releasing said connecting means from the welt bar, after release of tension thereon and while operating the machine to knit

fabric, by the combined action of the fabric on the welt bar and on the strap for the connecting means, and releasing the welt hooks from the fabric by hand and placing the welt bar in a position for the formation of another welt.

4. An auxiliary draw-off means for a full-fashioned knitting machine comprising in combination a shaft driven during knitting of an initial portion of fabric, a welt bar having a rearward and forward movement and having hooks engaging the first course of said portion of the fabric, stop means for said bar at the forward end of its path, a strap connected to said shaft and having a hook connected to said bar and applying a draw-off tension thereto, said hook acting to release the bar automatically upon continued knitting after the completion of the welt, and means for driving said shaft in the direction to apply a draw-off tension to said strap including a weighted connection so that tension is applied to said bar when against said stop means.

5. In a full-fashioned knitting machine having an automatic hooking-up and welt-turning mechanism, an auxiliary draw-off means comprising in combination a shaft driven during knitting of an initial portion of fabric, a welt bar having hooks engaging the first course of said portion of the fabric during the period required to knit it, stop means for said bar, a strap connected to said shaft and having a hook connected to said bar and applying a draw-off tension thereto during said period, said hook adapted to disengage itself from the bar upon knitting when its strap is slack and means for driving said shaft in the direction to apply a draw-off tension to said strap including a weighted connection so that tension is applied to said bar when against said stop means.

6. In a full-fashioned knitting machine, the combination of main and auxiliary draw-off means each including a shaft, said auxiliary means including a welt bar having hooks engaging the loops of the first course of an initial portion of the fabric and a strap connected to said auxiliary shaft and having a hook engaging said bar and applying a draw-off tension thereto during the knitting of said initial portion, a welt turning means operating upon completion of said portion to return the loops on said hooks to the needles to form a two ply welt, means operating to render inoperative said auxiliary draw-off means after completion of turning the welt and said main draw-off shaft operative to act when knitting additional fabric, and means relieving the tension on said strap by reversing the motion of said auxiliary shaft and holding the auxiliary shaft in the position to which it is turned by said reversing movement to permit said hook to disengage itself as the welt bar rides on the fabric during continued knitting of the fabric.

7. In a full-fashioned knitting machine, the combination of knitting needles, an auxiliary draw-off shaft having a reel fixed thereon, a welt bar having welt hooks thereon, a strap connected to said reel and having a hook connected to said bar at the start of knitting a fabric but adapted to disconnect itself therefrom upon continued knitting after the tension on said strap has been relaxed, means applying a draw-off torque to said shaft, pusher means acting to push said bar with said strap attached thereto and under tension into a position in which said hooks project between the needles when the welt is to be closed, means turning said shaft an angular distance

in the direction against said torque additional to that caused by pushing said bar to the welt closing position, and releasable means latching the shaft at the completion of said additional turning movement including a disk and a latch member normally bearing against said disk.

8. In a full-fashioned knitting machine having a means for pushing a welt bar into position for hooking up and closing a welt, the combination of an auxiliary shaft, means releasably connecting said bar and shaft, latch means for said shaft comprising a notched disk and a latch member, said disk and latch member permitting angular movement of said shaft in the direction the reverse of draw-off and holding said shaft against turning in the draw-off direction at the position reached by an angular movement in said reverse direction beyond that reached by the shaft when the welt bar is in the welt closing position.

9. In a full-fashioned knitting machine, in combination, a needle row, a welt bar having welt hooks thereon for engaging the loops of the first course, pusher elements on said bar for moving the loops of the first course toward the needle row when closing the welt, pusher means moving said bar toward the needle row when required, auxiliary draw-off means including a shaft connected to said bar during hooking-up, knitting and closing the welt, a pawl means acting to turn said shaft shortly after said closing in the direction the reverse of draw-off an angular distance additional to that which the shaft is turned by said pusher means when closing the welt, and releasable latch means engaging and holding said shaft after the shaft has been turned by said pawl means to cause the welt bar to become disconnected from the shaft.

10. In a full-fashioned knitting machine in combination, a welt bar, a main draw-off means, an auxiliary draw-off shaft, a strap connected to said shaft, a hook on said strap for connecting it to said bar, means for moving said bar in the non-draw-off direction to the needle row in position for closing the welt while the bar is connected to said shaft and thereby turning the shaft to a corresponding position, and means for turning said shaft further in the non-draw-off direction, latching said shaft at the end of said further movement and knitting while tensioning the fabric by said main draw-off means and while said shaft remains latched to cause said hook to disconnect itself from said bar.

11. In a full-fashioned knitting machine having a welt bar and an auxiliary draw-off means therefor, the combination of a pusher means adapted to move said bar toward the needle row and including pins acting to determine the position of the bar away from the needle row when the pusher means and bar are inactive, an auxiliary draw-off strap forming part of said auxiliary means, an auxiliary draw-off shaft forming part of said auxiliary means and connected to said strap, and means tending to turn said shaft to wind said strap on the shaft, said strap having springs connected to intermediate points thereof, said springs being under tension when said welt bar is against said pins and the pusher means is inactive.

12. In a method of operating a full-fashioned knitting machine having auxiliary and main draw-off means, a welt bar, a draw-off shaft forming part of said auxiliary means and having a reel thereon, a strap connected to said reel and

having a hook fixed thereon connected to said bar prior to hooking up the first course and a means for pushing said bar toward the needle row from a rest position to form a welt fabric and to disconnect the welt bar from the auxiliary draw-off means, the steps comprising moving the welt bar toward the needles so that its hooks extend between the needles while the auxiliary draw-off means is connected to the welt bar by said strap and its hook, hooking-up a first course and knitting a portion of a welt fabric while the welt bar moves in the draw-off direction, moving the welt bar toward the needle row but short of its hook-up position, placing a welt wire on the fabric and throwing the main draw-off tension on the welt wire to make a fold in the fabric, knitting the remainder of the welt while the main draw-off means is active and maintaining the welt bar stationary in said position, moving the welt bar toward the needles so that its hooks again extend between the needles and closing the welt, turning said shaft in the reverse direction to relieve the auxiliary draw-off tension, latching said shaft in such relieved position, knitting additional fabric while carrying the welt bar along with the fabric, and disconnecting said hook from said welt bar by the overall effects of knitting while the shaft of the auxiliary draw-off means is stationary.

13. In a full-fashioned knitting machine, the combination of a needle row, auxiliary and main draw-off means, a welt bar, a strap forming part of said auxiliary draw-off means and having a hook thereon connecting the strap to said bar during the knitting of the welt, pusher means acting to move said welt bar from a rest position to the needle row for hooking up the first course, guide means for holding a welt wire near the needle row, straps forming part of said main means and having hooks for connecting with said wire, means releasably latching said straps so that said last hooks engage said wire when unlatched, means causing said pusher means to move the welt bar to a position short of the needle row and the pusher means acting when so moved to unlatch said last straps, means causing said pusher means to hold said welt bar in said position short of the needle row until the welt has been knitted, means causing said pusher means to move said bar to the needle row and to hold it there until loops of the first course have been reengaged by the needles, said pusher means thereupon moving away from the bar to said rest position, and means causing said auxiliary draw-off means to relieve the tension in its strap following the closing of the welt to permit said first hook to disengage itself from the welt bar.

14. In a full-fashioned knitting machine, the combination of a needle row, auxiliary and main draw-off means, a welt bar, a shaft having a reel thereon forming part of said auxiliary draw-off means, a strap connected to said reel and having a hook thereon connecting the strap to said bar prior to hooking up the first course, pusher means acting to move said welt bar from a rest position to the needle row to hook up the first course, guide means for holding a welt wire in an initial position near the needle row, straps forming part of said main means and having hooks for connecting with said wire when held by said guide means, means causing said pusher means to move said bar to the needle row and to hold it there until loops of the first course have been reengaged by the needles to close the welt, said main draw-off means acting prior to

the closing of the welt to tension its said straps and to cause its said hooks to engage the welt wire, and means causing said auxiliary draw-off means to relieve the tension in its strap for a period of knitting following the closing of the welt, said last means including a notched disk on said shaft.

15. In a full-fashioned knitting machine, the combination of a needle row, auxiliary draw-off means including a shaft and a reel thereon, a welt bar, a strap connected to said reel and having a hook thereon connecting the strap to said bar during the knitting of the welt, means acting to move said welt bar to the needle row for hooking up loops of the first course, means acting to move the welt bar to the needle row and to hold it there until loops of the first course have been returned to the needles to close the welt, and means to relieve the tension in said strap following the closing of the welt to permit said hook to disengage itself from the welt bar, said last means including notched disks on said shaft.

16. In a full-fashioned knitting machine, the combination of a needle row, auxiliary draw-off means including a shaft and a reel thereon having a rest position, a welt bar having hooks thereon, a strap connected to said reel and having a hook thereon connecting the strap to said bar during the knitting of the welt, means acting to move said welt bar to the needle row for hooking up loops of the first course, means acting to move said welt bar to the needle row and to hold it there until loops of the first course have been returned to the needles to close the welt, means to turn said shaft to relieve the tension in said strap following the closing of the welt and to hold the shaft in a position reached by said turn, said last means including a disk on said shaft having a notch therein and a racking pawl for engaging said notch, said disk occupying a position when the welt hooks are at the needle row and the draw-off tension on said strap in which its notch is adapted to be engaged by said pawl, means normally holding said pawl away from its disk, a second disk fixed to said shaft and having a notch therein, a latch pawl for said second disk, the notches in said disks spaced an angular distance not more than that by which the shaft is turned by one racking action of said racking pawl, and means actuating said racking pawl at desired times and moving the racking pawl into engagement with the wall of said first notch and also in the direction contrary to the draw-off to permit said latching pawl to engage the wall of the notch in said second disk to hold said shaft stationary during continued knitting, and a second draw-off means acting during knitting after said shaft has been latched, said second disk having movement such that its notch stops short of the position of said latching pawl when the shaft is turned in the draw-off direction from its latched position to its rest position.

17. In a full-fashioned knitting machine, the combination of a needle row, auxiliary draw-off means including a shaft and a reel thereon, a welt bar having hooks thereon, a strap connected to said reel and having a hook thereon connecting the strap to said bar during the knitting of the welt, means acting to move said welt bar to the needle row for hooking up loops of the first course of a welt, means acting to move said welt bar to the needle row and to hold it there until loops of the first course have been returned to the needles to close the welt, means to turn said shaft to relieve the tension in said strap follow-

ing the closing of the welt and to hold the shaft in a position reached by said turn, said last means including a disk on said shaft having a notch therein and a racking pawl for engaging said notch, said disk occupying a position when the welt hooks are at the needle row and the draw-off tension on said strap in which its notch is adapted to be engaged by said pawl, means normally holding said pawl away from its disk, a second disk fixed to said shaft and having a notch therein, a latch pawl for said second disk, the notches in said disks spaced an angular distance not more than that by which the shaft is turned by one racking action of said racking pawl, and means actuating said racking pawl at desired times and moving the racking pawl into engagement with the wall of said first notch and also in the direction contrary to the draw-off to permit said latching pawl to engage the wall of the notch in said second disk to hold said shaft stationary during continued knitting, and a second draw-off means acting during knitting after said shaft has been latched, said second disk having movement such that its notch stops short of the position of said latching pawl when the shaft is turned in the draw-off direction from its latched position to its rest position.

18. In a method of operating a multi-section full-fashioned knitting machine having a main draw-off means, an auxiliary draw-off means including an auxiliary draw-off shaft used primarily during knitting of the welt, welt bars provided with hooks for engaging the fabrics, straps connected to said shaft and having hooks for connecting the straps with said bars, said main draw-off means including a main draw-off shaft and straps for connecting said main draw-off shaft to welt wires in folds of the welt fabrics to form a welt fabric and to disconnect the welt bar from the auxiliary draw-off means, the steps comprising closing the welts, discontinuing the draw-off action of said auxiliary shaft by turning the auxiliary shaft contrary to the draw-off direction to substantially relax the tension theretofore applied to the fabric by the auxiliary draw-off means, maintaining said auxiliary shaft near the angular position attained by it at the end of said turning while continuing to knit and to draw-off fabric by the main draw-off means until the hooks on the auxiliary straps have disconnected themselves from the welt bars, thereafter placing the welt bars in position for beginning a new set of blanks, reconnecting the hooks on the auxiliary straps with the welt bars, and maintaining enough tension on the auxiliary draw-off straps after their hooks have been reconnected to the welt bars to prevent the hooks from dropping off the welt bars.

HERBERT ERICH HAEHNE.
